C. L. RAYFIELD,
ENGINE SPEED REGULATING CARBURETER.
APPLICATION FILED SEPT. 8, 1917.

1,379,042.

Patented May 24, 1921.

UNITED STATES PATENT OFFICE.

CHARLES L. RAYFIELD, OF CHICAGO, ILLINOIS.

ENGINE-SPEED-REGULATING CARBURETER.

1,379,042.

Specification of Letters Patent. / Patented May 24, 1921.

Application filed September 8, 1917. Serial No. 190,326.

To all whom it may concern:

Be it known that I, CHARLES L. RAYFIELD, a citizen of the United States, residing at Chicago, in the county of Cook and State of Illinois, have invented certain new and useful Improvements in Engine-Speed-Regulating Carbureters, of which the following is a specification.

My invention relates to speed governors for internal combustion engines.

One of the objects of my invention is to provide a means of fuel control that is automatically operable by instrumentalities controlled by the usual engine functional effects whereby to prevent the main or power shaft of an engine from exceeding a predetermined speed of rotation.

A proper embodiment of my device is especially adaptable for use with trucks and other large, relatively ponderous vehicles, whereby a full flow of fuel to the cylinders of the engine, when the engine is fully loaded, is permissible to produce maximum effort at any speed within the predetermined limit at which the device may be set and locked and which will not permit speed in excess of the limit when the engine is running idle, as when the vehicle is not loaded.

In carrying my invention into effect I provide a carbureter in which the quality of the mixture is practicably constant and in which the volume of the charge, taken into the cylinders of the engine is controlled automatically, by the engine suction effect. The suction effect being adapted to operate the carbureter, modified by a speed responsive device operable by the engine.

Other and further objects of my invention will become readily apparent to persons skilled in the art from a consideration of the following description when taken in conjunction with the drawings, wherein:

Figure 1 is a plan view showing parts in section, of a carbureter and speed responsive device.

Fig. 2 is a transverse section taken on line 2-2 of Fig. 1.

In both views the same reference characters are employed to indicate similar parts.

In the specific embodiment illustrated by the accompanying drawings, 5 is a carbureter of the Rayfield type, as fully disclosed in an application filed by Charles L. Rayfield on the 21st day of June, 1917, identified by Serial No. 176,186. In this

form of carbureter a bellows diaphragm structure similar to the diaphragm 6 has its free end connected to the valves of the instrument so that the axial movement of the diaphragm serves to open and close the valves to vary the volume of the charge. The increased suction of the engine tends to collapse the diaphragm 6 somewhat, to a greater or less extent, thereby correspondingly opening the valves, whereas the valves will likewise be closed by a counter-acting spring when the suction effect produced by the engine is decreased in its action.

In the carbureter shown in the aforesaid application, 5 is a casing of the carbureter and 57 is a casing for the fuel control means, inclosing an axially contractile member, or airtight bellows diaphragm 6. The diaphragm structure 6 has one of its ends fixed to a hub 59, on the casing 57, by any suitable means. In the present instance it is shown as secured to a threaded nut 60 which is screwed upon the threaded hub 59. The wall 61 of the contractile diaphragm structure is therefore relatively stationary, while the other extreme wall 62 is capable of axial movement and is connected to a hollow piston 63, as by a threaded nut 64, or otherwise. The air-receiving chamber 65, of the carbureter, is tapered at its discharge end, as at 66, and is provided with an air-admitting opening 67. The piston 63 is capable of axial movement in an elongated hollow, inwardly-extending hub, or cylinder part 68, which is shown as an integral part of the casing 5. Secured to the piston 63, as at 69, is a fuel controlling needle valve 70. The needle valve is contained in an axial opening 71, in the hollow piston and moves with or as a part of the piston. An arm 72 extends from the wall of the casing 5 toward the axis of the discharge opening in the casing and supports a hollow, inwardly and outwardly tapered fixed tube 73, which is preferably screwed into the end of the hollow arm, as at 74. The tapered exterior surface of the tube fits in a similarly tapered axial opening in the piston 73. The interior of the tube 73 communicates with the fuel chamber in the float-containing casing 56, by a conduit or passage-way 75. The outer, free end of the piston 63 is provided with a laterally expanded part, forming a head 76, which serves as an air valve, for controlling the air valve port 77, to a greater or less

105

100

110

extent. The head, or valve 76, never at any time entirely closes the port 77, as shown. When the air valve 76 is drawn inwardly, in the tapered end 66 of the casing 5, the annular opening thus provided around the valve is of larger area, because the valve 76 has now been moved into a position where the diameter of the opening 66 is larger than the diameter of said opening in the transverse plane in which it is located, when the latter is in substantial closed position. The hollow hub 68 is annularly counter-bored, as at 78, to provide an air space through which air may pass from the transverse openings 79, in the hub 68. Openings 80 permit the air thus admitted, to enter the space 71, around the needle valve 70. A spring 82 surrounds the piston 63 and the hub 68, one end of which abuts against the wall 38 and the other end against the inner surface of the valve 76, thus tending to hold the air valve 76 in closed position, and the diaphragm structure 58 expanded, at the same time maintaining the fuel valve 68—70—73 more nearly but not quite closed, to shut off the supply of liquid fuel from the float chamber in which it is contained, to a greater or less extent.

In my improved device a conduit 7 communicates with the end of the carbureter 5, and is open to the suction effect produced by the engine. It communicates with the interior of the bellows diaphragm 6, through this conduit, a port 8 and an axial opening 9. The conduit, or opening 9, is controlled by a needle valve 10, which is connected to the free end of another bellows diaphragm 11, as at 12. The needle valve 11 is guided in the hub 13 so that it will always move in an axial path in response to contraction or expansion of the diaphragm 11. A bleeder port 14 is controlled by the set screw 15 to modify the effect of the suction, produced by the engine, upon the diaphragm 6.

The open helical spring 16 normally contracts the diaphragm 11 and retracts the needle valve 10, so as to leave the port 9 open to the fullest extent, when the diaphragm 11 is not affected by the operation of the engine. The tension of the spring 16 may be adjusted by the adjustable nut 17 and check nut 18 that are movable axially upon the threaded hub 13. The inner casing 19 is provided with a plurality of legs 20, 21, 22 and 23 leaving corresponding openings 24 between the respective legs, so as to render the nuts 17 and 18 accessible to adjust the tension of the spring 16. An outer casing 25 is provided with similar legs 26, 27, 28 and 29, somewhat larger in circumferential extent than the legs of the inner casing, so as to bridge the openings 24 between the legs of the inner casing when the casing 25 is rotated for the purpose. The rotatable casing 29 is provided with a projection 30,

perforated, as at 31, which is adapted to register with another projection 32 having a perforation 33 and fixed to a stationary part of the structure. A lock or seal may be passed through the registering perforations 31 and 33 so as to hold the outer casing in the position shown in Fig. 2 to render the interior adjustable mechanism inaccessible by unauthorized persons. 35 is a pump for the circulation of the cooling water of an automobile, connected by pipes 36 and 37, for completing the circulation of the water through the cylinder jackets and the radiator 28. The pressure produced by the pump 35, is practicably proportional to the speed of the engine. The pipe 36 is connected to the bellows diaphragm 11 by a branch pipe 39, so as to communicate the effect of the liquid pressure in the pipe 36 to the bellows diaphragm, to axially extend it against the resisting influence of the spring 16 when the pressure within the water system has been increased, by the speed of the engine, sufficiently to close the valve 10, in its port 9 to a greater or less extent, to reduce the effect of the diaphragm 6 in operating the fuel valves of the carbureter 5.

The effect of the carbureter 5 may also be varied by a needle valve 40, operable manually by a hand lever 41, the effect of which is to close or restrict the port 42 in the conduit 7, so as to modify the suction effect produced by the engine upon the expandable and contractile diaphragm 6.

The suction effect produced by the engine upon the initial rotation of its shaft, therefore, will be maximum, if the manual valve 40 be open, and will cause the diaphragm 6 to be contracted to its fullest extent, thereby opening the fuel and air valves in the carbureter 5. Upon rotation of the engine shaft the cooling water will begin to circulate in the water system including the pipes 36, 37, the engine cylinder, the radiator 38 and the pipe 39, thereby imparting considerable internal pressure to the bellows diaphragm 11 moving the free end axially against the resilient effect of the spring 16, and closing the valve port 9, by the needle valve 16, to a greater or less extent, in accordance with the pressure then existing in the said water system. Should the engine begin to run at a relatively high speed, the pressure in the water system will be increased to such an extent that the diaphragm 11 will be expanded and the port 9, controlling the opening into the diaphragm 6, will be substantially closed, so that the suction effect produced by the engine will no longer affect the diaphragm 6 to the same extent, and therefore the valve controlling the fuel, and operated by the diaphragm 6, will remain partially closed. If it is desired at any time to run the engine at a lower speed than that at which it is

maintained by the pressure speed responsive device 43, the lever 41 of the needle valve may be manually operated to close the port 42, to a greater or less extent, thereby correspondingly shutting off the effect of the suction upon the bellows diaphragm 6.

While I have herein shown a single embodiment of my invention, for the purpose of clear disclosure, it is manifest to persons skilled in the art, that many changes may be made in the general form and arrangement of the parts, within the scope of the appended claims.

Having described my invention, what I claim is:-

1. A carbureter having a fuel nozzle; a valve, operable by suction effect of the engine for controlling the nozzle; a sub-atmospheric motor responsive to the suction effect of the engine controlling said valve; another valve to vary the effect of the engine upon said motor and a speed variable means controlling the latter valve.

2. A carbureter having a fuel nozzle; a valve operable by the suction effect of the nozzle; an expansible diaphragm movable in response to the suction effect of the engine for controlling said valve; another valve controlling the effect of the engine on said diaphragm; another diaphragm communicating with a fluid medium moved by the engine to control the latter valve.

3. A carbureter having a fuel nozzle and an air admitting port; a bellows diaphragm having a port and operable in one direction by the suction effect of the engine; a spring to move it in the opposite direction; a valve for said nozzle and a valve for said air admitting port, movable by said diaphragm; a valve controlling said diaphragm port and means responsive to variation of engine speed for moving the diaphragm-controlling valve.

In testimony whereof I hereunto set my hand.

CHARLES L. RAYFIELD
